D. C. TERRY.
WASHING MACHINE.
APPLICATION FILED MAR. 6, 1913.

Patented May 5, 1914.

UNITED STATES PATENT OFFICE.

DAVID C. TERRY, OF GRUNDYVILLE, TEXAS.

WASHING-MACHINE.

1,095,604.

Specification of Letters Patent.

Patented May 5, 1914.

Application filed March 6, 1913. Serial No. 752,482.

To all whom it may concern:

Be it known that I, DAVID C. TERRY, a citizen of the United States, residing at Grundyville, in the county of Lampasas 5 and State of Texas, have invented certain new and useful Improvements in Washing-Machines, of which the following is a specification.

This invention relates to that class of 10 washing machines or apparatus in which the water is agitated by means of a reciprocating plunger, and thus forced through the clothes to effect the cleansing thereof.

It is the object of the invention to provide 15 a novel combination and arrangement of parts whereby a washing machine is had which is simple in construction and highly efficient in operation.

In order that the invention may be better understood, reference is had to the accompanying drawing, in which—

Figure 1 is a central vertical section of the machine. Fig. 2 is a horizontal section on the line 2—2 of Fig. 1. Fig. 3 is a horizontal section on the line 3—3 of Fig. 1.

Referring specifically to the drawing, 10 denotes a receptacle which is preferably made cylindrical and constructed of any suitable sheet-metal so that it may be used 20 as a boiler. In this receptacle is mounted a cylindrical drum 11 constructed of a single piece of sheet-metal, and arranged concentrically in the receptacle in spaced relation with the side wall thereof. The drum rises 25 from the bottom of the receptacle and terminates a short distance from the top thereof. In the side of the drum are vertical slots 12 which are for a purpose to be hereinafter described. The material at the edges of the 30 slots is bent back to form beads, thereby eliminating sharp edges which might tear the clothes. The slots permit a free circulation 35 of water from the receptacle into the drum and back into the former. The drum seats 40 loosely in the receptacle on the bottom thereof, and is held in place and centered by strips 13 secured at their upper ends to the receptacle on the inside thereof by bolts 14 and having their lower ends riveted or otherwise 45 fastened to the side of the drum near the bottom thereof. Upon removing the bolts 14, the drum can be removed from the receptacle for cleansing and other purposes.

The receptacle 10 has a lid 15 for tightly 50 closing the top thereof, said lid fitting snugly

in the receptacle and having on its under side a reduced portion 16 which fits snugly in the top of the drum 11 and thus serves to close the latter also. The lid rests on the top edge of the drum and its outer surface is flush with the top edge of the receptacle. Turn-buttons 17 carried by the receptacle are adapted to be swung over to engage the top of the lid and thus hold the same securely in place, and upon swinging said turn-buttons away from the lid, the latter can be removed. The reduced portion 16 of the lid not only makes a tight closure for the drum but also serves to hold the same firmly in place in the receptacle.

A reciprocatory plunger 18 works inside the drum 11, said plunger being carried by a stem 19 which passes through a central opening 20 in the lid 15 and rises a suitable distance above the latter. The plunger is a sheet metal disk having perforations 21, and on the bottom of the disks are wooden cleats 22 arranged radially. To the upper end of the plunger stem 19 is adjustably connected an operating lever 23 fulcrumed at 24 to a post 25 pivoted at 26 between ears 27 extending from the band or hoop 28 encircling the receptacle 10 at the top thereof and secured thereto in any suitable manner.

In operation, the clothes are placed in the drum 11 on top of the plunger 18 and the receptacle 10 is filled with soaped water up to within about one inch from the top of the drum. The lid 15 is now fastened down, after which the apparatus is ready for operation. The receptacle will be placed on a furnace or stove to bring the water to a boiling point. When the water is boiling, the plunger will be operated to carry the clothes up and down in the drum. This can be done without removing the apparatus from the furnace or stove. When the plunger ascends the water gushes through the perforations 21, and when the plunger descends the water again gushes through the perforations and lifts and loosens the clothes and they fill with water. At the end of the upward stroke, the clothes are pressed against the closure 16 of the drum, and the water is squeezed out. The water is thus kept agitated and forced through the clothes, and the cleansing operation is quickly effected. The water passes back and forth from the receptacle into the drum through the slots 12, which latter terminate close to

the top and bottom of the drum and thus extend, substantially, throughout the entire height thereof. The width of the slots is such that buttons which might pass thereinto will not be torn off as the clothes are forced up and down in the drum. The apparatus is very efficient and rapid in operation, and as it may be operated without taking it off the furnace or stove, the water may be kept boiling the entire time the plunger is being operated, whereby the cleansing operation is greatly facilitated.

The apparatus is simple in construction and easy to operate, and it therefore effectually serves the purpose for which it is designed.

The preferred embodiment of the invention has been shown, but it will be evident that many changes in the structural details may be made without a departure from the spirit and scope of the invention as herein-after claimed. The receptacle need not be

made cylindrical, but may be given any other shape.

I claim:

In a washing machine, a receptacle, a drum in the receptacle, said drum having longitudinal slots in its sides terminating near the top and bottom thereof, a closure for the top of the drum, means for locking the closure, and a reciprocatory perforated plunger in the drum on which plunger the clothes are supported and adapted to be carried against the aforesaid closure on the upstroke of the plunger; the aforesaid slots being co-extensive with the length of the stroke of the plunger.

In testimony whereof I affix my signature in presence of two witnesses.

DAVID C. TERRY.
